UNITED STATES PATENT OFFICE.

WILLIAM G. MILLER, OF DETROIT, MICHIGAN, ASSIGNEE TO THE R. C. MAHON COMPANY, OF DETROIT, MICHIGAN, A CORPORATION OF MICHIGAN.

ELEVATOR DOOR.

Application filed July 18, 1925. Serial No. 44,477.

This invention relates to doors, and relates particularly to vertically slidable elevator doors of the so-called "pass" type.

A well known door construction to which the invention is applicable comprises a pair of doors, meeting when closed midway of the height of a doorway, slidable from each other in their opening movement, and connected in a counter-balanced relation.

10 It is an object of the invention to provide a novel track construction for guiding a series of "pass" type doors and retaining such doors in open or closed position, and for effecting the necessary in or out movement of such a door, at one floor, as will when being opened or closed, avoid interference with doors at adjacent floors.

20 A further object is to provide co-acting members upon a sliding door other than its track-engaging rollers or the like, which in a certain position of the door will engage a projection carried by the track, for positively initiating a desired actuation of the door transverse to its main direction of 25 sliding travel.

These and various other objects the invention attains by the construction herein-after described and illustrated in the accompanying drawings, wherein:

30 Fig. 1 is a view in front elevation of a pair of "pass" type elevator doors equipped with the herein-described improved tracks, showing said doors in closed position.

Fig. 2 is a cross sectional view of the 35 same taken upon line 2-2 of Fig. 1.

Fig. 3 is a vertical sectional elevation taken upon the line 3-3 of Fig. 1, and showing one of the tracks with the closed position of the doors indicated in dash lines.

40 Fig. 4 is a similar view, sectionally showing the doors in their open position.

Fig. 5 is a fragmentary view showing how the lower end of the lower door is positively moved outwardly in a certain position of 45 said door.

In these views, the reference characters 1 and 2 designate upper and lower paired doors adapted, as will presently appear, to slide vertically to and from each other.

50 Each of said doors is provided, at its upper and lower ends, with pairs of guide rollers 3, journaled upon pins 4 projecting from the vertical edges of the doors, said pins being preferably carried by U-shaped brackets

5 which embrace the doors, and are rigidly secured thereto by suitable bolts 6.

The rollers 3 engage a pair of track members 7 which extend vertically, one at each side of the doorway, and each of said tracks comprises two flanges 8 and 8^a, between 60 which the corresponding rollers 3 are guided. The track members 7 extend continuously throughout substantially the entire length of the elevator shaft so as to coact with a series of doors located at the various floors of a building. The flanges 8 and 8^a form units, located one at each of the floors exemplified at 9 and 10, each unit projecting above and below the floor at which it is substantially centered, and being terminally spaced from the similar units located at each adjacent floor. Each unit 8, 8^a has its end portions slightly inclined away from the elevator shaft, as indicated at 11, and has 65 its ends closed.

70 The flange 8^a of each unit is intermediately formed with two adjacent upper and lower divergent pockets 12, extending parallel to the upper and lower end portions 11 of the unit, and terminating in vertical 75 alignment with the ends of the unit. (See Fig. 3.)

75 When the doors are in an open position, said rollers occupy the vertical portions of the guideways formed by the flanges 8 and 8^a.

80 Upon the adjoining ends of the doors 1 and 2, bars 13 are mounted which project terminally slightly beyond the doors for engagement by the ends of counter-balancing 90 chains 14, passing over chain wheels 15, mounted in brackets 16 carried at a suitable elevation by the tracks 7. The two doors thus being counterbalanced, one by the other, it requires only a slight effort to actuate 95 them vertically.

95 Preferably the lower portion of the lower door 2 carries a pair of sheet metal cam strips 17, spaced from the inner face of the lower edge portion of said door and inclining 100 toward said face as they extend upwardly. When said door is being closed, said cam strips engage a pair of projecting lugs 18 upon the flanges 8, and thus deflect the lower end of the door toward the landing, so as to assure engagement of the lower pair of 105 rollers 3 on said door in the upper pockets 12 of the guide unit.

Upon the flange 8^a of each guide unit, between the pockets 12 of said unit, there is provided a lug 19 which projects into the door opening and is engageable by the outer face of either door guided by said unit, in the opening movement of said door, to prevent a lower roller of a lower door from entering a lower pocket 12, or to prevent the upper roller of an upper door from entering an upper pocket 12.

What I claim is:

1. The combination with a sliding door, of guide rollers carried by said door, and spaced thereupon in the direction of travel of the door, of a track member engaged by said guide rollers, said track member having a portion slightly divergent to its length for receiving one of said rollers in the closed position of the door, and coacting members carried by the door and the track member independently of said rollers for compelling travel of the last mentioned guide roller into said divergent portion of the track when such travel is in the direction of divergency of said portion.

2. The combination with a sliding door, of a pair of guide elements carried by said door and spaced in its direction of travel, and a track engaged by said guide elements having a channel-shaped guide unit for receiving said elements, and an end portion of said unit being slightly divergent to the length of the unit to accomplish a lateral travel of one of said guide elements and a corresponding end of the door when the latter undergoes sliding travel, and one of the flanges of said track forming a U-shaped pocket extended parallel to said divergent end portion and engageable by the other of said guide members to effect a corresponding travel of the other end portion of the door.

3. The combination with a sliding door and a pair of guide elements carried by said door at one of its lateral edges, of a track member comprising a pair of flanges between which said guide elements are movable, said flanges meeting at corresponding ends to close the guide channel formed by said flanges and having their portions adjacent to said closure acutely inclined to the length of the channel to receive one of said guide elements, said channel being further formed intermediate of its length with a terminally closed pocket acutely inclined to the length of the track member in substantial parallelism to the first mentioned inclined portion, said pocket being adapted to receive the other of said guide elements.

4. The combination with a sliding door and a pair of guide elements carried by said door at one of its lateral edges, of a guide channel receiving said guide elements, and comprising a pair of parallel flanges, said track member further comprising a terminally closed branch guide channel extending

from one of said flanges and acutely inclined to the main guide channel, a projection upon the other flange substantially opposite the entrance to said pocket, and a cam member upon the door in an exterior relation to said guide channel engageable with said projection to deflect said guide element toward the entrance of said pocket.

5. The combination with a track member forming a main channel and forming a pair of branch channels diverging acutely from said main channel, of doors mounted upon said track members, guide elements upon said doors engaging in channels of said track member, and a projection upon said track member between said divergent branch channels engageable by a side face of one of said doors to restrain the guide element on said door from entrance into one of said branch channels.

6. The combination with a sliding door, of a pair of guide elements carried by said door and spaced thereupon in its direction of travel, a track member forming a channel adapted to receive said guide elements, said track member having a portion divergent to its length for receiving one of said guide elements in the closed position of the door and said track member being formed with a pocket opening from said channel and extending in substantial parallelism with said divergent portion of the track for receiving the other guide element in the closed position of the door, and a pair of co-acting members for shifting the last mentioned guide element into said pocket, one of said members being mounted upon said door independently of said guide element and the other being mounted upon the track member adjacent to said pocket.

7. The combination with a sliding door, of a pair of guide elements carried by said door and spaced thereupon in its direction of travel, a track member forming a channel adapted to receive said guide element, said track member having a portion divergent to its length for receiving one of said guide elements in the closed position of the door, and said track member being formed with a pocket opening from said channel and extending in substantial parallelism with said divergent portion of the track for receiving the other guide element in the closed position of the door, a member carried by said track member projecting therefrom in the direction of channel flanges and extending beyond said flanges and a projection carried by the door extending beyond a side face of said door to engage said projection on the track member to deflect the door transversely to its thickness and thereby enter the last mentioned guide element in said pocket.

8. The combination with two sliding doors located at adjacent floors of a building and adapted to overlap when one thereof is

opened, of a guide element carried by the lower portion of the upper door, a guide element carried by the upper portion of the lower door, a track member forming a channel in which said guide elements are adapted to travel, said track member being formed with a pair of pockets opening from said channel, and diverging from the channel, one upwardly to receive said guide element of the upper door and the other downwardly to receive said guide element of the lower door, and a common means carried by the track member for restraining the guide element on the upper door from entry into the downwardly divergent pocket and for restraining the guide element on the lower door from entry into the upwardly divergent pocket.

9. The combination with two sliding doors located at adjacent floors of a building and adapted to overlap each other when one thereof is opened, of a guide element carried by the lower portion of the upper door, a guide element carried by the upper portion of the lower door, a track member comprising flanges forming a channel in which said guide elements are adapted to travel, said track member being formed with a pair of pockets opening from one flange of said channel and diverging from said flange, one upwardly to receive said guide element of the upper door and the other downwardly

to receive said guide element of the lower door, and a projection upon the last named flange of said channel between said pockets engageable by both of said doors to restrain the guide element of the upper door from entry into the downwardly divergent pocket and to restrain the guide element of the lower door from entry into the upwardly divergent pocket.

10. The combination with a sliding door, of a pair of spaced guide elements upon said door, a track member engaged by said guide elements, having parallel spaced portions slightly divergent to the length of the track member and respectively engageable by said guide elements to actuate the door in or out during its sliding travel, a cam member carried by the door independent of said guide elements, and projecting beyond a side face of the door, and a projection upon the track member adjacent to one of said divergent portions extending into the path of travel of said cam member, and adapted by engagement with said cam member to shift the door transversely to said side face and to thereby engage one of said guide elements with the divergent portion of the track member, to which said projection is adjacent.

In testimony whereof I sign this specification.

WILLIAM G. MILLER.
